Baldwin, N.Y. 11510

Filed Mar. 5, 1969, Ser. No. 16,064

Term of patent 14 years

Int. Cl. D21—04

U.S. Cl. D34—5

FIG. 1

FIG. 2

FIG. 1 is a perspective view of a game indicator showing my new design;

FIG. 2 is a view similar to that of FIG. 1, with the article turned 180° from its position shown in that figure.

The conventional indicia is shown in broken lines for the purposes of illustration only and forms no part of the claim:

I claim:

The ornamental design for a game indicator, substantially as shown and described.
